PUNCH AND DIE ASSEMBLY

Thomas E. Hoskins, Moon Township, Allegheny County, Pa., assignor, by mesne assignments, to Raceways, Inc., New Brunswick, N.J., a corporation of Delaware

Filed July 28, 1961, Ser. No. 127,737

10 Claims. (Cl. 72—464)

This invention relates to a punch and die assembly. More particularly, it relates to a novel segmented die and punch assembly used to pierce and flare holes in underfloor duct work and assemble outlet cups thereto.

In underfloor electrical raceway systems it is frequently necessary to utilize underfloor ducts having outlets spaced periodically along its length. For example, it is quite common to utilize underfloor ducts having an outlet every two feet. For this purpose a ten foot duct would have five outlets. The manufacture of ducts having these spaced outlets is now a time consuming and expensive operation. The operation includes making a hole in the duct work, flaring the edges around the hole and fastening an outlet cap to the duct for each outlet opening. At present the hole is made by trepanning the duct. The trepanned duct is placed on a die and the edges are flared outwardly in two operations, part of the hole being flared in each operation. The outlet cup is then positioned on the flared edges and is fastened to the flared edges. This fastening operation also requires two steps. Thus, to fasten one outlet cup to a duct five operative steps are required.

This invention provides a novel punch and die assembly which will pierce the duct, flare the edges of the pierced hole and fasten the outlet cup to the duct in two operative steps. The duct is pierced and flared in one step and the outlet cup fastened to the pierced hole with one additional step. The entire operation can be accomplished in 20% of the time now required to fasten outlet cups to underfloor ducts by the methods currently used as described above.

Briefly stated, the invention consists of a die having laterally movable segments which support a solid die ring. The segments and the die ring are constructed with mating sides designed so that as the segments are extended laterally they force the ring member horizontally upward. The punch is designed to engage an actuating cam which in turn expands the segments causing the solid die ring to move upwardly. In one operation, the punch pierces the duct and the ring member flares the edges around the pierced hole upwardly. In the second operation, the ring member crimps the edges of an outlet cup to the flared edges of the hole thereby fastening the outlet cup to the duct.

In the accompanying drawings, I have illustrated presently preferred embodiments of my invention, wherein:

FIGURE 1 is a vertical section through a punch and die of this invention adapted and arranged to pierce and flare a duct;

FIGURE 2 is a vertical section similar to FIGURE 1 showing the punch and die in operative arrangement at the bottom of a stroke;

FIGURE 3 is a section on lines III—III of FIGURE 1;

FIGURE 4 is a horizontal section taken on lines IV—IV of FIGURE 2;

FIGURE 5 is a plan view of the die of this invention;

FIGURE 6 is a section on lines VI—VI of FIGURE 5;

FIGURE 7 is a vertical section similar to FIGURE 1 showing the punch and die of this invention arranged to fasten an outlet cup to the pierced and flared duct;

FIGURE 8 is a vertical section similar to that shown in FIGURE 2 showing the punch and die of this invention in operative relationship at the bottom of a stroke;

2

FIGURE 9 is an enlarged view of the junction formed between the outlet cup and the underfloor duct by the punch and die of this invention; and

FIGURE 10 is a vertical section showing the completed assembly of the outlet cup to the underfloor duct.

Referring to the drawings, a die, designated generally 10, is shown positioned in an underfloor duct 12. The die has a main die block 14 to which a base plate 16 is attached, forming a hollow central section 18 in the die block. An annular ring 20 formed from a plurality of segments 22 rests on the base plate 16. The segments are formed with a flat upper surface 24 and sloping sides 26 and 28. A groove 30 formed around the periphery of the segments holds a coil spring 32. The spring 32 biases the segments inwardly and holds them in a circular annular configuration. Their inward movement is restrained by a projection 34 formed at the central portion of the base member 16.

A solid annular die ring 36 rests on the outwardly sloping sides of the segments 22, and abuts the surface of the hollow central section 18 of the die block 14. The bottom surface of ring 36 which rests on segments 22 is sloped to mate with the sloping surface 28 of the segments. Thus, as the segments are expanded outwardly, 25 the solid die ring 36 will be raised.

Referring now specifically to FIGURES 1 and 2 which show the specific embodiment of the die of this invention adapted to pierce and flare the duct, the upper portion of the die ring 36 has an internal diameter equal to 30 the diameter of the hole to be pierced in the duct. The upper portion thus is of a much reduced diameter from the lower portion of the annular ring. The upper surface of the ring 36 has a short, flat section and an outwardly sloping section 38 and 40 respectively.

35 A central actuating cam 42 rests on the inwardly sloping surface 26 of the segmented ring and is held in position by a bolt 44 threaded into the base plate 16. The bottom surface of the central member 42 has a sloping surface which mates with the sloping surface 26 of the segments. As the actuating cam 42 is pushed downwardly, it forces the segments outwardly which in turn forces the die ring 36 upwardly. Again referring to the 40 embodiments shown in FIGURES 1 and 2, the central section in this embodiment has a circular rib 46 on the upper surface thereof. The die block 14 is formed with two vertically extending holes therethrough adjacent the hollow central section 18. T-shaped members 48 have their shanks inserted into the holes and are surrounded by coil spring 50 which are held to the T-shaped members 50 by buttonhead screws 52 which are fastened into the bottoms of the shanks. A circular groove 54 is cut out of the outer edge of the die ring 36 and the inner edge of the die block 14. The groove forms an outwardly extending ledge 55 in the ring 36 over which the head of the 55 T-shaped member 48 extends into the groove. Thus, as the die ring 36 is forced upwardly by the expanding segmented ring 20, it engages the head of the T-shaped member forcing it upwardly and compressing the coil spring 50. When the actuating force is withdrawn allowing the segments to retract, the spring 32 pulls the 60 segments back into their original ring-like position and the springs 50 force the annular die ring 36 back into its original position.

The die block 14 also has two horizontally extending holes 56 therethrough. As best seen in FIGURE 6, these holes house side gauge assembly 58. The assembly consists of a set screw 60 and a gauge pin 62 separated by a coil spring 68. The die block is formed with narrow projections 64 and 65 on each side thereof.

70 The projection 64 acts as a bearing surface. When the die is inserted in the duct, the gauge pin 62 forces the projection 64 into contact with the inner surface of the

duct. Thus, as the die 16 is inserted in the duct 12, it is positioned at the desired longitudinal position in the duct by the side gauge 53. The tapered front end 66 of the pin 62 extends beyond projection 65, but if the pin 62 is worn or the spring 63 is operating improperly, the projection will act as an emergency bearing surface.

The die block is formed with a longitudinal hole extending from one end into the hollow central section which houses a tube 69 which in turn is connected to a source of air so that air may be forced through the hollow central section.

The punch of this invention has inner and outer members movable with respect of each other. In FIGURES 1 and 2 the punch used in the piercing and flaring operation is specifically shown. It consists of a support member 70 to which an inner punch member 72 is fastened by bolt 74. The face of member 72 has a circular groove around the periphery to conform with the rib 46 on the actuating cam of the die. It is annular and has a diameter equal to the diameter of the hole to be pierced in the duct. The edges are at right angles and are cutting edges. An annular member 76 is positioned around the member 72 and is fastened to member 70 by means of bolts 78 which extend through member 70 and are threaded into the annular member 76. Coil springs 80 surround bolts 78 and abut the head 70 and annular member 76. Stops 82 are fastened by means of bolts 84 to the head 70. Thus, member 76 may be moved with respect to member 72 until it abuts members 82 as shown in FIGURE 2. After the force causing the movement is eliminated, springs 80 return the members 72 and 76 to their original position as shown in FIGURE 1. The bottom surface of the member 76 is cut at an angle at the point where it abuts the member 72 as shown at 86.

In operation, the member 72 hits the duct 12 piercing the hole therein and hitting the member 42 forcing it down and expanding the segments 22 forcing the annular ring member 36 upwardly which flares the edge of the pierced hole as shown in FIGURE 2. After the operation is completed and the operating force removed, the springs 32, 50 and 80 return the members to the original position shown in FIGURE 1. The stops 82 prevent excessive movement of the member 72 with respect of the member 76. The peripheral rib 46 bends the cutout section 89 of the duct 12 so that it does not bind in the opening and will be elevated when the position is returned to normal. As the actuating force is removed, an air stream is automatically turned on, forcing air through a tube 69. The blank 89 is elevated above the die block by the air stream and is blown away from the assembly by a second horizontal air stream (not shown).

Referring now to FIGURES 7 and 8 showing the specific embodiment of the punch and die of this invention adapted to fasten an outlet cup to the pierced and flared duct, the die ring 36 (FIGURE 1) is replaced by a modified die ring 36a. The ring 36a cooperates with segments 22 in the same manner as does the ring 36. The upper portion of the die ring 36a is of a different configuration than that of ring 36. The inner diameter of ring 36a is less than the inner diameter of ring 36. The outer edge of ring 36a is formed with a radius 91 and a chamfer 93.

The actuating cam 42 (FIGURE 1) is replaced by an operating cam 42a. The cam 42a operates on segments 22 in the same manner as cam 42. However, cam 42a does not have a rib on the upper surface thereof. The upper surface of the cam 42a is flat.

The punch used with the die for assembling an outlet cup to the duct has a head 70 to which is bolted a T-shaped spacing member 90. An operating head 92 is fastened to the base of the T-shaped member 90 by means of bolt 94. An outer member 96 encircles the T-shaped member 90 and is movable with respect thereto. A coil spring 98 encircles the shank of the T-shaped member 90 and abuts the head of member 90 and member 96. When the punch has no force applied to it, the coil spring 98

forces the member 96 against head 92. When force is applied to the head 70 of the punch, the spring will be compressed and the members 90 and 92 move with respect of the member 96. The extent of the motion is limited by the head of T-shaped member 90 which will stop the movement by contact with the member 96. The diameter of the member 96 is just slightly less than the internal diameter of the outlet cup to be fastened to the duct.

The outlet cup to be fastened to the duct is made with a bifurcated end which is pinched on the flared duct. As shown in FIGURE 7 the outlet cup has two legs 100 and 102 which rest on either side of the flared duct. The bifurcated structure provides a shoulder 104 at the junction of the two legs 100 and 102. The lower end of member 96 of the punch is formed with an offset at its outer perimeter which provides a shoulder 106. As the punch is inserted into the outlet cup, the shoulder 106 mates with shoulder 104 holding the outlet cup firmly in the place as the member 92 continues hitting the operating cam 42a forcing the segments outwardly and raising the die ring 36a. As the die ring 36a is raised, the radius 91 on the edge of the die ring catches leg 102 of the outlet cup bending it outwardly—crimping it firmly against the internal surface of the flared hole in the duct. The chamfer 93 on the edge of the die ring provides clearance between the ring 36a and the leg 102 so that the crimping will be completed. At this point the punch and die set is in the position shown in FIGURE 8. The springs 98, 59 and 32 return the parts to their original position when the actuating force is removed. The finished duct with the outlet cup firmly attached thereto is shown in FIGURE 10.

From the foregoing it is apparent that the improved punch and die of this invention makes possible the assembly of an outlet cup to the floor ducts in two quick operations. The duct is pierced and flared outwardly in one stroke of the punch and the outlet cup is assembled to the pierced and flared hole in one action of the punch. This substantially reduces the time required to assemble an outlet to the duct work. The art now has a separate piercing or trepanning operation. Two separate operations of a punch and die are required to flare the duct and two operations of the punch are required to attach the outlet cup thereto.

While I have described the present preferred embodiments of my invention, it should be understood that it may otherwise be embodied within the scope of the following claims.

I claim:

1. A punch and die assembly comprising a die member having a plurality of laterally movable, spring mounted segments forming an annular segmented ring, the sides of the segments sloping outwardly forming inner and outer bearing surfaces, an actuating cam resting on the inner bearing surface of the segments and movable downwardly to expand the segmented ring, and a solid annular die ring resting on the outer bearing surface of the segments, the die ring being raised by lateral movement of the segments, and a punch having inner and outer members movable with respect to each other, the inner member being adapted to contact the actuating cam and force it downwardly.
2. A punch and die assembly comprising a die member having a die block having a hollow central cavity, a base plate attached to the die block, a plurality of laterally movable segments forming an annular segmented ring positioned on the base plate in the hollow cavity of the die block, each segment having a groove in its side providing a peripheral groove around the segmented ring, a coil spring mounted in the peripheral groove inwardly biasing the segmented ring, an actuating cam resting on the segments and movable downwardly to expand the segments, an annular die ring resting on the segments and having a groove cut in its outer surface, the die ring being raised by lateral movement of the segments, a T-

shaped member positioned in the die block adjacent the hollow central cavity, the head of the T-shaped member extending into the cavity and engaging the groove in the die ring, a coil spring mounted on the shank of the T-shaped member downwardly biasing the T-shaped member, and a punch adapted to contact the actuating cam and force it downwardly.

3. A punch and die assembly for piercing and flaring underfloor ducts comprising a die member dimensioned to fit inside an underfloor duct, said die member having a die block having a hollow central cavity, a base plate attached to the die block, a plurality of laterally movable segments forming an annular segmented ring positioned on the base plate in the hollow cavity of the die block, the segmented ring being biased inwardly, an actuating cam resting on the segments and movably mounted to the base plate, the cam being movable downwardly to laterally expand the segmented ring, an annular die ring resting on the segments, the inner diameter of the upper portion of the annular die ring being equal to the diameter of the hole to be pierced and the outer edge of the upper face of the ring sloping downwardly and outwardly, the die ring being raised by lateral movement of the segments, and a punch having outer and inner members movable with respect of each other, the outer member having an internal diameter equal to the inner diameter of the die ring and having its inner edge cut off, and the inner member fitting inside the outer member and being adapted to pierce the duct contact the actuating cam and force it downwardly, the downward movement of the cam expanding the segments forcing the die block upward, the outer edge of the die block and the inner edge of the outer punch member cooperating to flare the edge of the pierced hole.

4. A punch and die assembly for piercing and flaring underfloor ducts comprising a die member dimensioned to fit inside an underfloor duct, said die member having a die block having a hollow central cavity, a base plate attached to the die block, a narrow longitudinal projection extending from at least one side of the die block, at least one side gauge extending transversely through the die block, the side gauge having a spring mounted gauge pin extending from the side opposite the side from which the longitudinal projection extends, the gauge pin seating the projection against the inner surface of the duct, a plurality of laterally movable segments forming an annular segmented ring positioned on the base plate in the hollow cavity of the die block, an actuating cam resting on the segments and movably mounted to the base plate, the cam being movable downwardly to expand the segmented ring, an annular die ring resting on the segments, said die ring being raised by lateral movement of the segments, and a punch adapted to pierce the duct and force the cam downwardly whereby the die ring is elevated flaring the edges of pierced hole in the duct.

5. A punch and die assembly for piercing and flaring underfloor ducts comprising a die member dimensioned to fit inside an underfloor duct, said die member having a die block having a hollow central cavity, a base plate attached to the die block, a plurality of laterally movable segments forming an annular segmented ring positioned on the base plate in the hollow cavity of the die block, the segmented ring being biased inwardly and the sides of the segments sloping outwardly forming inner and outer bearing surfaces, an actuating cam resting on the inner bearing surface of the segments and movably mounted to the base plate, the cam being movable downwardly to laterally expand the segmented ring, an annular die ring resting on the outer bearing surface of the segments, the inner diameter of the upper portion of the annular die ring being equal to the diameter of the hole to be pierced and the outer edge of the upper face of the ring sloping downwardly and outwardly, the die ring being raised by lateral movement of the segments, and a punch having outer and inner members movable

with respect to each other, the outer member having an internal diameter equal to the inner diameter of the die ring and having its inner edge cut off, and the inner member fitting inside the outer member and being adapted to

5 pierce the duct contact the actuating cam and force it downwardly, the downward movement of the cam expanding the segments forcing the die block upward, the outer edge of the die block and the inner edge of the outer punch member cooperating to flare the edge of the pierced hole.

10 6. A punch and die assembly for piercing and flaring underfloor ducts comprising a die member having a die block having a hollow central cavity, a base plate attached to the die block, a plurality of laterally movable

15 segments forming an annular segmented ring positioned on the base plate in the hollow cavity of the die block, the segmented ring being biased inwardly, an actuating cam resting on the segments and movably mounted to the base plate, the cam being movable downwardly to

20 laterally expand the segmented ring and having a rib around the periphery of its upper surface, an annular die ring resting on the segments, the inner diameter of the upper portion of the annular die ring being equal to the diameter of the hole to be pierced and the outer edge of

25 the upper face of the ring sloping downwardly and outwardly, the die ring being raised by lateral movement of the segments, and a punch having outer and inner members movable with respect of each other, the outer member having an internal diameter equal to the inner diameter

30 of the die ring and having its inner edge cut off, and the inner member fitting inside the outer member and having a groove around the periphery of its face and being adapted to pierce the duct contact the actuating cam and force it downwardly, the downward movement

35 of the cam expanding the segments forcing the die block upward, the outer edge of the die block and the inner edge of the outer punch member cooperating to flare the edge of the pierced hole, and the rib on the actuating cam and the groove in the inner punch member

40 cooperating to bend the blank.

7. The punch and die assembly defined in claim 6 in which the die has an air tube extending through the die block and into the central cavity, and the air tube is connected to a source of air whereby the blank may be forced

45 out of central cavity by an air stream.

8. A punch and die assembly for assembling an outlet cup to a flared edge of a hole in an underfloor duct, the outlet cup having a bifurcated end which fits around the flared edge, the assembly comprising a die member having

50 a plurality of laterally movable segments forming an annular segmented ring, the sides of the segments sloping outwardly forming inner and outer bearing surfaces, an actuating cam resting on the inner bearing surface of the segments and movable downwardly to laterally

55 expand the segmented ring, a solid annular die ring resting on the outer bearing surface of the segments, the outer edge of the die ring being cut-off to form an inner radius and an outer chamfer, the die ring being raised by lateral movement of the segments, and a punch having

60 inner and outer members movable with respect to each other, the outer member being adapted to grip the outlet cup and hold it in position and the inner member being adapted to force the actuating cam downwardly expanding the segmented ring and forcing the die ring upwardly, the inner radius of the die ring crimping the bifurcated end of the outlet cup to the flared edge of the duct.

9. A punch and die assembly for fastening an outlet cup to a flared edge of a hole in an underfloor duct, the

70 outlet cup having a bifurcated end which fits around the flared edge and provides an internal shoulder on the outlet cup, the assembly comprising a die member having a die block having a hollow central cavity, a base plate attached to the die block, a plurality of laterally movable segments forming an annular segmented ring

positioned on the base plate in the hollow cavity of the die block, the sides of the segments sloping outwardly forming inner and outer bearing surfaces and the segmented ring being inwardly biased, an actuating cam resting on the inner bearing surface of the segments and being movably mounted to the base plate, the cam being movable downwardly to laterally expand the segmented ring, a solid annular die ring resting on the outer bearing surface of the segments, the outer edge of the die ring being cut-off to form an inner radius and an outer chamfer, the die ring being raised by lateral movement of the segments, a punch having inner and outer members movable with respect to each other, the outer member having an offset at its outer perimeter providing a shoulder adapted to grip the shoulder on the outlet cup and hold the cup in position and the inner member being adapted to contact the actuating cam forcing it downwardly and forcing the die ring upwardly whereby the inner radius of the die ring crimps the bifurcated end of the outlet cup to the flared edge of the duct.

10. A punch and die assembly for fastening an outlet cup to a flared edge of a hole in an underfloor duct, the outlet cup having a bifurcated end which fits around the flared edge, the assembly comprising a die member dimensioned to fit inside an underfloor duct, said die member having a die block having a hollow central cavity, a base plate attached to the die block, a narrow longitudinal projection extending from at least one side of the die block, at least one side gauge extending transversely through the die block, the side gauge having a spring

5
